FORMING BULGED RECEPTACLES

Clare L. Hinsdale, Warren, Ohio, assignor, by
mesne assignments, to Mullins Manufacturing
Corporation, Salem, Ohio, a corporation of New
York

Application April 13, 1937, Serial No. 136,568

4 Claims. (Cl. 113—48)

The invention relates to the manufacture of receptacles having a bulged portion in the side wall thereof, and more particularly to the formation of a sheet metal receptacle closed at one end and having a bulged corrugated portion in the side wall and extending from the closed end.

Such receptacles are particularly useful as washing machine tubs, in which it is desirable that the bulged portion extend from or merge with the closed end of the tub, and it is also desirable that the bulged portion be corrugated.

It is therefore a principal object of the present invention to provide an apparatus and method for forming a bulged and/or corrugated portion in the side wall at the closed end portion of a sheet metal receptacle.

Certain prior constructions have provided for forming a bulged portion on a receptacle, but if the bulged portion is to be corrugated it can not be formed at the closed end of the receptacle by such prior constructions.

It has been proposed to provide radially expanding dies for forming a bulged portion in sheet metal receptacles, but such dies can not form the bulged portion at and extending from the closed end of the receptacle, because the dies necessarily occupy the space adjacent the closed end and do not support the end wall for maintaining its shape during the forming of the bulged portion in the side wall. Thus, while such dies might be used to form a bulged and/or corrugated portion intermediate the ends of a receptacle, they can not form a bulged and/or corrugated portion at and extending from the closed end of a receptacle.

It has also been proposed to form a series of substantially vertical corrugations in the side wall of a receptacle by rolling, stamping or pressing one or more corrugations successively around the periphery of the side wall, but this results in the metal of the side wall becoming gathered or drawn inwardly rather than being stretched or bulged outwardly.

Other prior constructions for forming corrugations have included the provision of a punch cooperating with a female die having ribs thereon, but these constructions produce scratches in the side wall of the receptacle so as to render them unfit for being coated by vitreous enamel, which is frequently desired; and these constructions are not suitable for forming a bulged portion in the receptacle side wall.

It is therefore a further object of the present invention to provide an apparatus and method for making a bulged corrugated portion merging

with and extending from the closed end of a receptacle, which will overcome all of the foregoing difficulties and which will produce a bulged corrugated portion suitable for being coated with vitreous enamel.

Another object is to provide an apparatus which will produce the bulged portion and the corrugations thereon at one and the same time.

Another object is to provide an apparatus which will form the corrugations in the bulged portion of the receptacle in such a way that the metal is stretched or bulged outwardly.

When sheet metal receptacles having integral side and bottom walls are utilized as washing machine tubs, it is frequently desirable to form special offset and drainage formations in the bottom wall prior to bulging and/or corrugating the side wall.

It is therefore a further object of the present invention to provide apparatus for forming a bulged and/or corrugated portion in the side wall of a sheet metal receptacle, without distorting the previously formed bottom wall formations.

And finally, it is a general object of the present invention to provide an apparatus and method for forming a bulged corrugated portion merging with and extending from the closed end of a sheet metal receptacle, which will accomplish all of the foregoing objectives and inexpensively and efficiently produce receptacles having an attractive and distinctive appearance.

These and other objects are obtained by the parts, elements, combinations and arrangements of the apparatus, preferred embodiments of which are shown in the accompanying drawings, and by the methods and procedure comprising the present invention; all of which are hereafter set forth in detail and defined in the appended claims.

In general terms the invention includes the provision of outer die means and inner die means between which the receptacle is received, said inner die means having a bottom wall holding die and parts which are expansible radially downward on the bottom wall holding die to cooperate with the outer die means in forming a bulged corrugated portion in the receptacle side wall merging with and extending from the receptacle bottom wall.

Referring to the drawings forming part hereof Figure 1 is a vertical sectional view of the improved apparatus as on line 1—1 Fig. 2, showing the dies in the position forming the bulged corrugated portion in the receptacle, the outer die means being shown fragmentarily;

Fig. 2 is a plan sectional view substantially on

line 2—2, Fig. 1, showing the expandible inner die members in elevation with the punch removed;

Fig. 3 is a fragmentary sectional view as on line 3—3, Fig. 1, showing the sliding wedging connection between the punch and one of the expandible inner die members;

Fig. 4 is a sectional view similar to Fig. 1, showing the punch slightly withdrawn and the expandible inner die members partially contracted;

Fig. 5 is a fragmentary sectional view as on line 5—5, Fig. 2, showing the spring means for contracting the inner die members as the punch is withdrawn;

Fig. 6 is an elevation on a reduced scale of the finished tub;

Fig. 7 is a plan sectional view similar to Fig. 2, showing the tub before being formed and located between the inner die members in contracted position and the outer die members in expanded position;

Fig. 8 is a fragmentary sectional view as on line 8—8, Fig. 7;

Fig. 9 is a plan sectional view taken substantially on line 9—9, Fig. 1 showing the inner bottom wall die in full lines;

Fig. 10 is a fragmentary sectional view substantially on line 10—10, Fig. 1; and

Fig. 11 is a fragmentary sectional view substantially on line 11—11, Fig. 5.

Similar numerals indicate corresponding parts throughout the drawings.

While the improved apparatus shown and described herein is adapted for forming a bulged corrugated portion in the side wall of a sheet metal receptacle, the invention comprehends the forming of a bulged portion without corrugations, or the forming of corrugations in the receptacle side wall without bulging the same.

The improved apparatus preferably includes a base plate 12 on which is mounted the bottom die plate 13 for supporting and conforming to the previously formed outer contour of the bottom wall 14 of a deep drawn sheet metal receptacle having a preferably integral tubular side wall 15.

The base plate 12 supports expanding female or outer die segments 16, which are circumferentially arranged to conform to the side wall 15 of the receptacle, and the segments 16 have hollowed or concave portions 17, on which are formed the desired ribs and grooves (Fig. 7), for cooperating with inner die members to form a bulged corrugated portion in the receptacle side wall.

The outer die segments 16 are arranged to be contracted radially by downward movement of a series of die wedging members 18 which have bevelled surfaces 19 cooperating with bevelled surfaces 20 on the die segments to force the segments radially inward against the receptacle side wall 15.

The die wedging members 18 may be secured as by screws 21 to the flange portion 22 of an annular punch-receiving die member 23, which fits within and conforms to the inner surface of receptacle side wall 15. The wedging members 18 and die member 23 are moved in unison vertically up and down by a usual press connecting plate indicated at 24.

A stripper plate 25 is located under the flange 22 when the dies are assembled, for engaging the rim flange 26 of the receptacle for stripping the same from die member 23 as it is withdrawn. The stripper plate 25 is preferably secured by screws 27 to a spacing ring 28 which abuts the

upper surfaces of wedging members 18 during the forming operation.

The construction and arrangement of the die members thus far described in themselves form no part of the present invention, and are substantially according to usual and well known practice in the art.

As shown, the bottom wall 14 of the deep drawn sheet metal receptacle has a stepped or offset formation to which the upper surface of the bottom die plate 13 conforms, and the inner die means preferably includes a bottom wall inner die plate 30 having a bottom surface conforming to the inner contour of the receptacle bottom wall.

The inner die plate 30 is generally frustoconical in shape, and is shown in plan elevation in Fig. 9 of the drawings. The upper surfaces of said die plate 30 include a plurality (preferably four) of downwardly inclined, preferably cylindrical, identical surfaces 31 spaced alternately with a like number of downwardly inclined, cylindrical surfaces 32. The cylindrical surfaces 31 and 32 preferably extend or taper from a central, preferably horizontal surface 33, radially outward and downward to the outer periphery of the die member 30.

Preferably each surface 31 has a radially disposed downwardly inclined guide member 34 secured therein and projecting upward therefrom and the guide members 34 are slidably received in elongated grooves 35 formed on the lower surfaces of each of a plurality of expandible forming die members 36. The expandible members 36 are substantially diamond-shaped when viewed in plan, as shown in Figs. 2 and 7, and are provided, if so desired, at their outer peripheries with narrow convex corrugated portions 36a for engaging the side wall 15 of the receptacle.

The bottom surfaces 37 of the expandible members 36 are cylindrical to slidably conform to the inclined cylindrical surfaces 31 on the bottom die plate 30, and the upper surfaces 38 of the members 36 are also cylindrical to slidably conform to similar inclined cylindrical surfaces 39 formed on the bottom of the punch-receiving die member 23, as clearly as shown in Fig. 10.

The expandible inner die means also includes a plurality (preferably four) of identical forming die segments 40 which are located between the members 36, and have convex outer surfaces 40a with corrugations, if so desired, formed thereon for engaging the receptacle side wall 15. The segments 40 are substantially pie-shaped in plan elevation and cooperate with the members 36 to provide a circumferentially complete continuous corrugated convex or bulged portion or die surface for forming a complementary bulged portion in the receptacle side wall when the expandible members 36 and segments 40 are expanded as shown in Fig. 2.

The segments 40 are provided with cylindrical bottom surfaces 42 for slidably conforming to the inclined cylindrical surfaces 32 on the die plate 30, and have cylindrical upper surfaces 43 for conforming to similar inclined bottom cylindrical surfaces 44 on the punch-receiving die member 23, as shown in Fig. 11.

The punch-receiving inner die member 23 and the inner bottom die plate 30 are preferably secured together in vertical spaced relation by spaced bolts 46 extending through spacer sleeves 47 and located between adjacent die members 36 at the inner sides radially of segments 40. The bolts 46 are preferably screwed into die plate 75

30 at their lower ends and secured at their upper ends by nuts 48 to interior flanges 49 on the die member 23 (Figs. 5 and 8).

Thus the die member 23 and the bottom die plate 30 constitute a male or inner die having adjoining downwardly and outwardly inclined channels in which the expandable die members 36 and die segments 40 move or expand outwardly to engage the receptacle side wall 15 at a position merging with and extending upwardly from the receptacle bottom wall 14.

The guides 34 slidably engage in grooves 35 to guide the die members 36 radially during their outward movement, and the outer angular or tapered surfaces 50 of each member 36 slidably and cooperatively abut an inner angular or tapered surface 51 of each of two adjoining segments 40 to drive and guide the segments 40 during their outward and inward movement.

Preferably, each segment 40 is provided at its inner side radially with an arcuate notch 52 for fitting an adjacent spacer sleeve 47. Means for yieldingly urging the segments 40 radially inward to engage the notches 52 with the spacer sleeve 47 preferably includes springs 53 located at opposite sides of each sleeve. The springs 53 may be secured at their inner ends to a cross bar 54 engaged behind said sleeve, and their outer ends may be received in suitable bores 55 in the inner side of each segment 40 and connected to pins 56 screwed in the segments and extending into the inner ends of the bores.

Means for moving the expandable diamond-shaped members 36 outward against the receptacle side wall 15 preferably includes a punch die 58 having a tapered wedge engagement with said members 36. The punch 58 preferably has four diametrically opposite downwardly and inwardly inclined surfaces 59 which are substantially parallel with the inner inclined surfaces 60 of the expandable die members 36, and the surfaces 59 are arranged to be closely adjacent to surfaces 60 when the punch is moved downwardly to the position shown in Fig. 1.

Each surface 59 has secured thereon, as by screws 61, a wedge plate 62 having a T-shaped groove 63 therein, and the surface 60 of each member 36 has secured thereon, as by screws 64, a T-shaped key 65 for slidably fitting in the groove 63 adjacent thereto.

Thus the wedge plate 62 and interfitting keys 65 form sliding wedge abutments between the punch 58 and the expandable die members 36, whereby relative downward movement of the punch forces the members 36 outwardly and downwardly on the inclined cylindrical surfaces 31, of bottom plate 30, the guides 34 sliding in the slots 35 to guide the members 36 radially.

As the members 36 move outwardly, the angular or tapered surfaces 50 thereof slidably abut the angular or tapered surfaces 51 of the adjoining pie-shaped segments 40 to force the segments outwardly and downwardly on the inclined cylindrical surfaces 32 of the bottom die plate 30, against the tension of springs 53.

In the operation of the improved apparatus, the deep drawn sheet metal receptacle having a straight cylindrical side wall 15, as indicated in cross section in Fig. 7 and partially in dot-dash lines in Fig. 4, is positioned on the outer bottom die plate 13 within the outer die segments 16 in their expanded position as shown in Fig. 7. The stripper plate 25 and spacer ring 28 are then placed in position as shown in Fig. 4, and the die members including the punch 58, inner die mem-

bers 23, 30, 36 and 40, together with the outer die wedging members 18 are all moved downwardly to occupy the positions shown in Fig. 4. In this position the outer die wedging members 18 have forced outer die segments 16 to their contracted position against and completely surrounding the bottom portion of the receptacle side wall 15.

As the punch 58 continues to move downwardly to the position of Fig. 1, the inner die members 36 move outwardly and in turn force and guide the pie-shaped segments 40 outwardly to the position of Figs. 1 and 2, in which the convex corrugated outer surfaces 36a and 40a of the members 36 and 40 respectively, form a circumferentially complete continuous bulged die portion which cooperates with the concave portions 17 of the outer die members 16 to form the bulged corrugated portion 15a in the receptacle side wall 15, as shown in Figs. 1 and 2 in full lines, and in dot-dash lines in Fig. 7.

As shown in Figs. 1 and 4 the bulged portion 15a merges with and extends upwardly from the bottom wall 14 of the receptacle, because the tapered or inclined surfaces 31 and 32 terminate at the very bottom of the side wall and permit the die members 36 and 40 to expand the side wall beginning at its intersection with the bottom wall. Moreover, the downwardly inclined movement of the expandable die members on the bottom die plate 30 results in subjecting the side wall to increased expanding pressure.

During the outward movement of the die members 36 and 40, the inner bottom die plate 30 holds and maintains the bottom wall 14 of the receptacle against the outer bottom die plate 13 in its previously formed shape, and the downwardly inclined cylindrical surfaces 31 and 32 on the plate 30 permit the bulged portion to be formed as merging into and extending from the receptacle bottom wall.

As the punch is moved upwardly after the forming operation, the wedge connections with the members 36 first draw the members 36 inwardly to the position of Fig. 4, and at the same time the springs 53 move the segments 40 inwardly until the expandable die members again occupy a position similar to that shown in Fig. 7. The punch 58 and inner die members 23, 36, 40 and 30, together with the outer die members 18, may then be withdrawn, during which operation the outer die wedging segments 16 expand and the stripper plate 25 engages the top flange 26 of the receptacle to strip the receptacle from the inner die member 23. The finished receptacle is shown in Fig. 6 and has the desired bulged corrugated portion in its side wall merging into and extending from its bottom wall.

I claim:

1. In apparatus for forming a bulged corrugated portion in the side wall of a sheet metal receptacle having a bottom wall, an inner die member for conforming to said side wall, an inner bottom die member secured to said inner die member in vertically spaced relation for conforming to and clamping said receptacle bottom wall, said inner die member and said bottom die member having parallel downwardly and outwardly inclined guiding surfaces, and expandable die members having cooperatively abutting tapered surfaces and slidably engaging said guiding surfaces for movement into abutment with said receptacle side wall at said bottom wall.

2. Apparatus for forming a bulged corrugated portion in the side wall of a sheet metal receptacle, including outer die means for providing a

- circumferential concave corrugated die portion, an inner bottom wall die member having downwardly inclined upper surfaces, expansible inner die members having circumferential convex corrugated portions slidably supported on said inclined upper surfaces for movement radially outward and downward and being so constructed as to form a circumferentially complete continuous corrugated die surface when so moved to cooperate with said outer die means in forming a bulged corrugated portion in the receptacle side wall, and individual guide means on the bottom wall die member for said expansible die members.
3. In apparatus for forming a bulged corrugated portion in the side wall of a sheet metal receptacle having a bottom wall, a downwardly tapered inner bottom die for conforming to and clamping said bottom wall, expansible die members movable radially outward and downward on said bottom die having corrugated forming surfaces, punch means wedgeably engaging said expansible die members for expanding them into bulging engagement with said receptacle side wall at said receptacle bottom wall, said die

members being so constructed as to present when expanded a circumferentially complete continuous corrugated die surface, and individual guide means on the bottom die for the expansible die members.

4. In apparatus for forming a bulged corrugated portion in the side wall of a sheet metal receptacle having a bottom wall, an inner die member for conforming to said side wall, an inner bottom die member secured to said inner die member in vertically spaced relation for conforming to and clamping said receptacle bottom wall, said inner die member and said bottom die member having parallel downwardly and outwardly inclined guiding surfaces, expansible die members having cooperatively abutting tapered surfaces and slidably engaging said guiding surfaces for movement into abutment with said receptacle side wall at said bottom wall, and punch means wedgeably engaging said expansible die members for moving the same on said guiding surfaces.

CLARE L. HINSDALE.
